BLASTING EXPLOSIVE ASSEMBLY

William F. Wilson, Newark, Del., assignor to
 Atlas Powder Company, Wilmington, Del., a
 corporation of Delaware

Application May 4, 1939, Serial No. 271,772

9 Claims. (Cl. 102--24)

This invention relates to improvements in blasting explosive assemblies, and more particularly to improvements in explosive assemblies of the general character of those described in U. S. Letters Patent to Carl D. Pratt, No. 1,785,529.

The aforesaid patent discloses the many important advantages flowing from an assembly having a core of high explosive material, such as dynamite, and a body of low explosive, such as black powder, surrounding said core. By virtue of such a combination, an assembly is provided in which there is incorporated the sensitivity and strength of the high explosive core, with the reliability, safety, and non-shattering explosive action of the black powder.

However, the Pratt patent discloses the black powder incorporated in the form of pellets, the high explosive core material being co-extensive in length and individual to the several pellets. In such an arrangement, there is little likelihood of the dynamite getting out of longitudinal alignment, because the pellets themselves, when enclosed in a suitable wrapper, are of such a nature as to maintain their position and thereby maintain the position of the dynamite of the core.

The present invention proposes to employ a suitable container having a central core consisting of two or more sticks of dynamite disposed end to end in longitudinal alignment, with a surrounding body of black powder. It also contemplates the use of an aligning tube within which the sticks of dynamite are contained. This tube or equivalent centering means functions to keep the sticks of dynamite in centered and end to end relation to each other.

It is also contemplated to utilize this idea of a centering means for a plurality of superimposed sticks of dynamite in a bag-like container, the walls of which are made of waterproof and extensible material. When used in such a container, the central tube not only serves its function of centering the sticks of high explosive material, but it aids in preventing such localized impacting of the black powder as would tend to produce such localized bulges upon the exterior of the container as would interfere with the proper loading of the explosive assemblies into bore holes.

The body of black powder which surrounds the superimposed sticks of high explosive is not separated into distinct layers, as in the case of pelleted black powder, but comprises a filled-in, homogeneous mass which in length equals the combined length of the sticks of high explosive. If it were attempted to place a plurality of sticks of high explosive in longitudinal alignment without some means of maintaining the position of these sticks in the body of black powder, it is almost certain that in handling and transit,

some of these sticks would get out of line. They might lie obliquely of the package, or they might assume positions where they would lie wholly or partly side by side.

5 Any such dislodgement of the high explosive core would be highly undesirable, because one of the important functions of this central core is to propagate the explosive wave from one detonator assembly to another when a plurality of them are loaded into a bore hole on top of each other. The closer the end of the high explosive core of one assembly lies to the end of the corresponding core of another assembly, the more reliable and certain will be the action of the detonating wave 10 through the whole group of assemblies.

15 It will be seen that my proposed arrangement efficiently serves to accomplish this proper positioning of the units of the high explosive core with respect to each other. Further objects and 20 advantages of the invention will be set forth in the detailed description which follows.

In the accompanying drawing:

Figure 1 is a sectional view of an explosive assembly employing a bag-like container of extensible material;

25 Fig. 2 is a horizontal sectional view upon line 2—2 of Fig. 1;

Fig. 3 is a horizontal sectional view illustrating a modified form of spacing element;

30 Fig. 4 is a magnified view illustrating a section of the extensible wall of the bag-like container of Fig. 1, and

Fig. 5 is a vertical sectional view illustrating an assembly employing a rigid container.

35 Like numerals indicate corresponding parts in all of the figures of the drawing.

In the drawing, 1 designates a bag-like receptacle that is tied at the top by a conventional twisted wire loop 2. This loop embodies the conventional eye 3 by which the assembly may be lowered into a bore hole. A body of granular black powder 4 surrounds a tube 5, said tube being held in centered relation within the bag by annular spacers 6. These may be made of cardboard, Celluloid, or any other suitable material. When made of Celluloid, they have the advantage that they may be consumed along with the explosive charge.

40 The tube 5 receives a plurality of sticks, usually two or three, 7, of high explosive material such as dynamite. Referring now to Fig. 4, 1^a designates a web of extensible paper, of the nature of crepe paper, for example. This paper is covered by a coating of a suitable water-proofing composition 1^b, such as latex, asphalt, or the like. This material 1^b is not only water-proof, but it is sufficiently adhesive to closely unite an outer web of woven fabric 1^c to the paper web 1^a.

45 The fabric 1^c gives a considerable degree of 50 strength to the walls of the container without

impairing the flexibility and extensibility of the material of said walls. Thus the assembly as a whole has such a degree of flexibility and elasticity as will best adapt it to be tamped tightly into bore holes. At the same time, in the absence of tamping pressure, the outer wall of the container maintains its straight line form to adapt it to be lowered into bore holes without catching upon the sides of the hole.

This straight line formation of the otherwise easily deformed container 1 is maintained in part by the presence of the tube 5. This tube aids in maintaining a more uniform impacting of the black powder and aids in preventing localized density variations in said powder, such as might tend to cause localized bulges of the extensible wall 1^a.

The structure illustrated in Fig. 3 is substantially like that already described, except that in lieu of the solid spacers 6, I employ a wire spacing element 6^a which serves to maintain the tube 5 in centered relation to container 1. This spacer 6^a has the advantage that the black powder may be filled into the container with this spacer in place, because this spacer is an open one through which the black powder may pass.

It will generally be desired to employ a container having extensible walls, because of the advantages arising from the capability of assemblies employing such containers to be tamped into and conform to the contour of the bore holes in which they are placed or to the contour of the other assemblies which go to make up a large charge. However, it is within the purview of the invention to employ a rigid outer container if desired, and such an arrangement is illustrated in Fig. 5.

Here the low explosive charge is indicated at 8, and the sticks of high explosive are indicated at 9^a, 9^b, 9^c, and it is also indicated that these explosive sticks may have individual wrappers 9^d. In this case, the outer container 10, of tubular formation, is closed at its lower end by a cap 11. This cap may be provided with an upstanding annular flange 12 to receive and position the central tube 13 by which the high explosive sticks are aligned.

The upper end of this tube is positioned in a corresponding flange 14 upon a cap 15. The assemblies of both Figs. 1 and 5 may be dipped in paraffin after completion to aid in sealing them and rendering them wholly water-proof. The container of Fig. 5 will be of somewhat can-like formation and may be made of tin, paper, Celluloid, or any other suitable material.

Where the container 10 and its caps 11 and 15 are made of pyroxylin compositions, they have the advantage of being consumed along with the remainder of the charge. With this end in view, I may make the tubes 5 and 13 of pyroxylin materials which, while having sufficient strength to serve their function of centering, may be quickly consumed along with the remainder of the charge and thus avoid an undue amount of smoke.

I may, in the construction of Fig. 1, employ dynamite sticks 7 either with or without wrappers. Conventional sticks of dynamite are eight inches in length, and I contemplate utilizing these conventional sticks of dynamite in the manufacture of the explosive assembly of this invention.

It is to be understood that the invention is not limited to the precise constructions shown, but that it includes within its purview whatever changes fairly come within either the terms or the spirit of the appended claims.

Having described my invention, what I claim is:

1. In an explosive assembly, a container, a tubular member extending lengthwise through said container, a plurality of sticks of high explosive disposed end to end within the tubular member, and a continuous mass of loose, low explosive within the container and surrounding said tubular member.

10 2. A structure as recited in claim 1, in combination with spacing members bearing between the container wall and the tubular member by which the tubular member is held in substantially centered relation within the container.

15 3. A structure as recited in claim 1, in combination with a spacer for holding the tubular member in centered relation in the container, said spacer being of open formation to permit the passage of the low explosive therethrough in filling the container.

20 4. In an explosive assembly, the combination with a high explosive core consisting of a plurality of conventional sticks of dynamite disposed end to end in contacting relation, of a centering tube within which said sticks of dynamite are located, an elongated bag-like container of a length equal to the combined length of the sticks of dynamite, the walls of which container are of extensible and water-proof material, and a body of low explosive completely filling the space within the bag around said tube and presenting a continuous and unbroken body of said low explosive of a length to overlap all of said sticks of dynamite.

25 5. A structure as recited in claim 4, in combination with means for centering the tube in the container.

30 6. In an explosive assembly, the combination with a high explosive core consisting of a plurality of conventional sticks of dynamite disposed end to end in contacting relation, of a centering member within which said sticks of dynamite are located, an elongated bag-like container of a length equal to the combined length of the sticks of dynamite, within which said dynamite sticks and centering member are located, the walls of which container are of extensible material, and a body of low explosive completely filling the space within the bag around said centering member and presenting a continuous and unbroken body of said low explosive of a length to overlap all of said sticks of dynamite.

35 7. A structure as recited in claim 6 wherein the centering member is formed of combustible material.

40 8. A structure as recited in claim 6, wherein the extensible wall of the container comprises an internal layer of extensible paper, an external layer of extensible woven fabric, and an intermediate uniting layer of water-proof cementitious material between the paper and fabric.

45 9. In an explosive assembly the combination with an elongated bag-like container of water-proof material, of a plurality of sticks of high explosive disposed end to end lengthwise of said container and substantially centrally therein, and an aligning means of a length to overlap a plurality of said sticks of high explosive, engaging said sticks of explosive and holding them from shifting laterally out of alignment with each other, and a body of granular low explosive surrounding the high explosive and substantially filling the container.

50 70 WILLIAM F. WILSON.
